UNITED STATES PATENT OFFICE

146,933

DESIGN FOR A SCREEN OR THE LIKE

Jack Wolf, Washington, D. C.

Application December 7, 1945, Serial No. 124,435

Term of patent 7 years

(Cl. D33—1)

To all whom it may concern:

Be it known that I, Jack Wolf, a citizen of the United States, residing at Washington, in the District of Columbia, have invented a new, original, and ornamental Design for Screen or the like, of which the following is a specification, reference being had to the accompanying drawing, forming part thereof.

Figure 1 is a front elevational view of a screen showing my new design; and

Figure 2 is a top view thereof.
The rear of the screen is plain.

I claim:
The ornamental design for a screen or the like, as shown and described.

JACK WOLF.
